GUARD FOR LOOSE LEAF BINDERS

Albert D. Sutton, San Antonio, Tex.

Application April 14, 1933, Serial No. 666,195

6 Claims. (Cl. 129—19)

This invention relates to a new type of guard for any size or type of looseleaf binder and is especially adapted to large record books such as deeds, records and the like, in which the pages 5 are of the looseleaf type and are, or may be, inserted from time to time as the book is filled until the book is completed. The guards may be fastened to the binder by means of a post or posts or they may be sewed together and bound in book 10 form.

In some looseleaf binders as at present constructed the sheet is carried directly by the posts. Because of this fact, when a large looseleaf record book is completed a large portion of the space 15 closest to the post is wasted on account of the fact that the sheet or leaf cannot lie flat when the book is opened.

A main purpose of the present invention is the saving of this space which is now wasted because 20 the leaves or sheets being carried directly by the posts cannot lie flat when the book is opened, while the leaves or sheets in the looseleaf book using the guard of this invention will lie flat when the book is opened and the entire sheet will be 25 usable and visible as well as readable regardless of what place the book is opened. In other words the new guard accomplishes for a looseleaf binder what is now accomplished in a regularly bound book.

30 A main purpose of the invention is to provide an intermediate element which extends between the post and the leaves of the book. This intermediate element is carried by the posts and the leaves are hingedly secured to a hinged portion 35 upon the intermediate element.

With these and other objects in view as will become apparent as the description proceeds, the invention consists in the combination of parts and elements set forth in detail below, claimed in the 40 claims and shown in the drawings, in which

Figure 1 is a side elevational view of a guard with leaves attached,

Figure 2 is a partial elevational view of the center of the leaves in opened position,

45 Figure 3 is a sectional view taken upon the section lines 3—3 of Figure 1 looking in the direction of the arrows.

Figure 4 is a cross sectional view taken upon the section lines 4—4 of Figure 1 looking in the direction of the arrows,

50 Figure 5 is a plan view of a portion of the locking pin,

Figure 6 is a cross sectional view illustrating a modified form of locking the locking pin to a hinge,

Figure 7 is a plan view of a portion of the locking pin used in the modification shown in Figure 6.

Figure 8 is a side elevational view of a modification in which a guard constructed of metal is 66 used.

Figure 9 is a partial elevational view of the central portion of the modification shown in Figure 8,

Figure 10 is a partial elevational view of the 65 sheets in open position with parts shown in section illustration a modified form of locking device for the locking pin,

Figure 11 is a cross sectional view taken on the section line 11—11 of Figure 8 looking in the direction of the arrows, and

Figure 12 is a cross sectional view taken on the section line 12—12 of Figure 8 looking in the direction of the arrows.

Referring to the drawings in which like reference characters indicate like parts throughout the various figures, 19 indicates the guard generally and is composed of two parts 11 and 12. The part 11 comprises interior layers 13 of cardboard or the like covered upon each side with cloth or 75 fabric 14 which extends over and covers the interior layers 15 of cardboard or the like disposed within the part 12 of the guard. The cardboard layers 13 and 15 which may be jute tag or the like are spaced a short distance from one another 80 as shown particularly in Figures 3 and 4 so as to provide a hinge 16 extending from the top to the bottom of the guard composed entirely of the cloth or fabric 14. The layers 13, 15 and the cloth fabric 14 are secured together by adhesive 85 or fasteners of any type desired. The part 11 of the guard is provided with apertures 17 designed to receive the posts of the looseleaf binder.

The above construction describes the guard itself which is secured to the posts of the binder 95 in the same manner as loose leaves are at present secured. In case the binder does not use posts, then the part 11 of the guard is modified so as to be secured to whatever type of securing means is used by the binder.

The construction whereby the leaves are secured to the part 12 will now be described. The cloth fabric 14 preferably extends around the inside edge 18 of the part 12 and the edge 18 is cut out at the portions 19 so as to leave the portions 20 which form hinges for the reception of a locking pin 21. The loose leaves 22 are also provided with cut-out portions 23 designed to accommodate the hinge portions 20 of the part 12.

The locking pin 21 passes through the hinge 110

portion 20 as shown particularly in Figure 2 of the drawings and has a flattened portion 24 located preferably at one of the hinge portions 20 and this flattened portion 24 is provided with an aperture 25 through which extends a locking brad 26, shown more particularly in Figure 3. The loose leaves 22 are of the double leaf size and the apertures 23 are placed at the central portion thereof. Each guard accommodates a plurality of leaves.

By means of the construction set forth above it is obvious that the book may be opened at any desired place and the leaves when opened will lie in substantially flat condition.

In Figures 6 and 7 a modification of the locking pin 21 is shown according to which the locking pin has an enlarged portion 27 provided with an annular groove 28. The locking brad 26 in this case instead of passing through an aperture, fits into the groove 28. It may if desired be flattened into said groove by a blow after the locking pin has been properly positioned.

In Figures 8, 9, 10, 11 and 12 a further modification of the guard is shown making the same adaptable to the use of steel or any other suitable metal. As above described with reference to the construction shown in Figure 1, the modified guard comprises two elements 30 and 31 which are composed of metal and, since they are composed of metal, they may be hinged together by means of hinges 32 through which passes a locking pin 33 which may be secured in position by means of the flattened portion 24, the aperture 25 and the locking brad 26, as previously described.

The part 30 is provided with apertures 17 as in the previous modification, or any means rendering the same capable of being secured to the binder. The steel guard may if desired for ornamental purposes, be covered with cloth or finished in any desired way.

Upon the inward edge of the part 31 hinges 34 are provided to which the leaves 22 are secured by the locking pin 35 of the same type as previously described. The pin 35 is provided with the flattened portion 24, the aperture 25 and the locking brad 26, as previously described and shown more particularly in Figure 9.

In Figure 10 a modification of the locking pin particularly adapted for the metal construction is shown. In this modification the locking pin 35 is provided with a threaded portion 36 and one of the hinges 34 is threaded to accommodate the threaded portion 36 and after the threaded portion 36 has engaged the threaded portion of the hinge 34, the threads may be distorted by a blow from a hammer or other instrument so as to permanently lock the two together. It is obvious that various types of locking means may be employed in both constructions for securing the locking pin to the various types of hinges provided.

Various advantages follow from the use of the above construction and these may be briefly set forth as follows. The entire sheet may be used,

the book can be easily opened, ease and comfort is provided by reading a page lying perfectly flat, the ease with which a soiled page or sheet may be replaced is increased since it is merely necessary to remove such page from its respective guard and not release the entire binder and lastly, a greater protection is provided against tearing. It will be noted that an essential characteristic of the invention resides in the providing of a double hinge for each sheet of paper.

80

85

It is understood that the above embodiments are merely the preferred embodiments and are not to be construed in a limiting sense, but all embodiments such as will fall clearly within the scope of the appended claims are to be included within the scope of the invention.

90

I claim:—

1. A guard for looseleaf binders comprising a first member, a second member hinged to said first member, hinge sockets upon said second member to which loose leaves may be attached, a locking pin for securing said loose leaves to said sockets and means for locking said locking pin to one of said sockets.

95

2. A guard for looseleaf binders comprising a first member for securing the guard to the binder, a second member hinged to said first member, a locking pin cooperating with said second member for securing loose leaves pivotally to said second member, a flattened portion upon said locking pin and a brad extending through said second member and said flattened portion to secure said locking pin to said second member.

100

3. A guard for looseleaf binders comprising a sheet metal member, a second sheet metal member pivotally secured to said first member, a screw threaded socket upon said second member and a locking pin having a threaded portion cooperating with said screw threaded socket for securing loose leaves to said second member.

110

4. A guard for looseleaf binders comprising a first member, a second member pivoted to said first member, hinged sockets upon said second member to which loose leaves may be attached, a locking pin for securing said loose leaves to said sockets and means for locking said locking pin to secure said loose leaves in position.

115

5. A guard for looseleaf binders comprising a first member, a second member hinged to said first member, hinge sockets upon said second member to which loose leaves may be attached, a locking pin for securing said loose leaves to said sockets and means for locking said locking pins to secure said loose leaves in position.

125

6. A guard for looseleaf binders comprising two parts hinged together, means upon one of said parts for securing loose leaves thereto, said last named means comprising a locking pin having an enlarged portion with a groove therein and means cooperating with said groove for maintaining said locking pin locked to said member.
